ATTORNEY

UNITED STATES PATENT OFFICE.

WILLIAM F. OTTO, OF WILKES-BARRE, PENNSYLVANIA.

GLASS GAGE FOR BOILERS.

1,121,656.

Specification of Letters Patent. Patented Dec. 22, 1914.

Application filed March 9, 1914. Serial No. 823,357.

To all whom it may concern:

Be it known that I, WILLIAM F. OTTO, a citizen of the United States, and a resident of Wilkes-Barre, county of Luzerne, State of Pennsylvania, have invented certain new and useful Improvements in Glass Gages for Boilers, of which the following is a specification.

My invention relates to an improvement 10 in glass gages for boilers.

It relates more particularly to gages of the character in which a detachable glass plate constitutes one side of a passage-way for holding water, and it has for its object 15 to provide an improved construction of means for detachably but securely holding the glass plate in proper position.

A further object is to provide a means of such character that the glass plate is not 20 liable to be fractured.

Other objects and advantages of my invention will be referred to in the detailed description which follows or will be apparent therefrom.

25 In order that my invention may be more readily understood reference should be had to the accompanying drawings illustrating a convenient embodiment thereof. It will be understood, however, that changes in the 30 details of construction may be made within the scope of the claims without departing from my invention.

In the drawings:—Figure 1 is a longitudinal section of a gage construction embodying my invention; Fig. 2 is a front elevation of the same, the pipe connections therewith being omitted; Fig. 3 is a top plan view of the same, one of the pipe connections being shown in section; and Fig. 40 4 is a transverse section on the line 4—4 of Fig. 2.

Referring to the drawings, 1 designates a plate member, preferably of metal, provided at its rear side with a swell or enlargement 45 2 extended longitudinally and centrally of the plate. The opposite edges of the plate 1 are provided with forwardly extending flanges 3 the outer sides of which flanges are slightly convergent. The inner sides, however, are parallel with respect to each other. The front edges of the flanges 3 are provided with inwardly extending portions 4 constituting shoulders or ribs upon the inner sides of the outer front edges of said 50 flanges.

The opposite ends of the swelled or enlarged portion 2 are somewhat enlarged as indicated at 5 and 6; also the upper and lower ends of the passage-way formed by such swelled or enlarged portion are closed 60 by material 7 and 8 which material is provided with openings 9 and 10 communicating respectively with pipes 11 and 12 which in turn communicate with a boiler, not shown.

65 15 designates a plate of glass or other transparent material which is seated against the surface of the plate upon opposite sides of the passage-way formed by the swelled or enlarged portion 2 and between the 70 flanges 3. The plate 15 is first placed in proper position by hand and then is securely held in position by means of a relatively long flat wedge 16 the central portion of which is cut away as shown at 17. The opposite edges of this wedge engage the shoulders or beads 4 upon the inner sides of the front edges of the flanges 3. It should be noted that these shoulders or beads incline 75 slightly from their bottom upwardly so that the width of the space between the inner surfaces of the said shoulders and the confronting surface of the plate 1 is somewhat greater at the bottom of said plate than 80 at the top.

85 In order that the glass plate 15 may effectually close and seal the front side of the passage-way formed by the swelled or enlarged portion 2, I provide a washer or packing 18 of suitable material which is 90 substantially of the same shape as that of the glass plate and its central portion is cut away in order that the view through the glass to the water in the said passage-way shall not be disturbed. Also in order to 95 prevent the wedge 16 from contacting directly with the glass, I have provided an outer washer 20 which is of substantially the same shape and construction as that of the washer 18. The washer 20 is, as will be 100 seen upon an examination of the drawings, situated between the outer side portions and the upper end portions of the wedge 16 and the confronting portions of the front side of the glass 15.

105 In order to draw the wedge into position and clamp it firmly against the glass plate 15, I have provided the upper edge of the wedge with a screw-threaded stem 21 which extends through a washer 22 which is seat- 110

ed upon the upper edges of the flanges 3. The inner rear edge of the washer is cut away as indicated at 23 to form an angular groove or seat for the reception of the upper front edge of the closure 7. The wedge 16 is drawn into and held in position by means of nuts 25.

It will be understood that the water passes from the boiler through the pipe 12 into the space or passage-way formed by the enlarged or swelled portion 2 of the plate 1. The height of the water in the boiler may be ascertained by observation through the glass plate 15 in the usual and known manner.

15 By the employment of a construction embodying my invention, as above described and illustrated in the drawings, I have found that the glass plate is securely and efficiently held in place in such manner as to prevent leakage of water from the passage-way closed thereby and also that the said plate is so protected from the wedge 16 and that the pressure exerted by said wedge upon the glass is so evenly distributed upon 25 the glass that the latter is not subjected to uneven strains so that it is not likely to become fractured or broken.

I claim:

1. A gage for boilers comprising a member having a groove formed upon one side thereof, flanges upon the opposite edges of said member, the outer edges of said flanges being provided with inwardly extending portions forming shoulders, the inner surfaces of said shoulders being inclined from one end toward the other, a transparent plate seated against the said member and closing the groove therein, and a wedge interposed between the said plate and the said shoulders for holding the said plate in position.

2. A gage for boilers comprising a metallic plate having a groove formed and extending longitudinally thereof, the said plate being provided with forwardly extending flanges at its opposite edges which flanges are provided with inwardly extending shoulders at their outer edges, the inner surface of said shoulders being inclined from one end toward the other, a glass plate seated against the surface of the said metallic plate between the said flanges and closing one side of the groove formed in said plate, a washer interposed between one side of the glass plate and the metallic plate, and a wedge interposed between the other

side of the glass plate and the said shoulders and holding the said glass plate in position.

3. A gage for boilers comprising a metallic plate having a groove formed therein and extending longitudinally thereof and also having flanges at its opposite edges, the front edges of said flanges being provided with inwardly extended shoulders the surfaces of which incline from one end toward the said metallic plate, a glass plate interposed between the said shoulders and the said metallic plate for closing one side of the groove in said plate, and washers upon the front and rear sides of the said glass plate, the central portions of which washers are removed, the rear washer being interposed between the said metallic plate and the opposing side of the said glass plate, a wedge interposed between the said shoulders and the other side of said glass plate and being seated against the said front washer for holding the said plate in position, the central portion of the said wedge being removed, and means for securing the said wedge in position against the said glass plate.

4. In a gage for boilers, the combination of a plate having a groove therein extending longitudinally thereof and provided with closures at its opposite ends having openings therethrough, the said plate being provided with longitudinal flanges at its opposite edges which flanges are provided with inwardly extending shoulders at their front edges, which shoulders are inclined longitudinally, a glass plate seated against one side of the said first named plate between the said flanges and closing the said groove, a washer seated upon the upper ends of the said flanges, a wedge interposed between the said shoulders and the said glass plate, the said wedge having a stem extending through a hole in said washer, and nuts engaging the said stem and contacting with the said washer, the said nuts being adapted to draw the said wedge firmly in position against the said glass plate and the said shoulders and to hold the same in position.

In testimony that I claim the foregoing as my invention I have hereunto signed my name this 23rd day of January, A. D. 1914.

WILLIAM F. OTTO.

In the presence of—

G. W. WILMOT,

Wm. LLOYD.
